CONVERSION OF HYDROCARBON OILS

Jacque C. Morrell, Chicago, Ill., assignor, by
mesne assignments, to Universal Oil Products
Company, Chicago, Ill., a corporation of Dela-
ware

Application December 1, 1930, Serial No. 499,281

3 Claims. (Cl. 196—48)

This invention relates to the conversion of hydrocarbon oils, and relates more particularly to the conversion of relatively heavy oils into lighter and more valuable products.

5 Among the objects of the invention is to provide a process and apparatus wherein a wide flexibility of operation in the treatment of hydrocarbon oils may be effected, depending upon the nature and characteristics of the oil and 10 the results desired. The invention contemplates an operation wherein relatively high yields of distillates, such as motor fuel and the like, with relatively small yields of substantially dry coke and gas may be effected, 15 as well as an operation wherein, in addition, substantial quantities of residual oils, such as fuel oil and the like, are produced. The residual products of the operation may be so treated within the system as to effect their reduction to asphalt-like materials.

I have found that these results may be obtained by varying the operating conditions under which the invention may be practiced in treating a great variety of charging stocks, and 25 this flexibility of operation and the results obtainable thereby are among the important features of my invention.

The primary concepts of the invention may comprise subjecting hydrocarbon oils to a conversion temperature in a heating element, introducing the heated material into an enlarged reaction chamber, withdrawing the products of reaction from said reaction chamber and introducing the same into a vaporizing chamber, 35 preferably maintained under a reduced pressure, subjecting the vapors from said vaporizing chamber to fractionation to effect separation of the desired relatively light portions from the relatively heavy, insufficiently converted portions thereof, subjecting said relatively light portions to condensation and cooling, collecting the resultant distillate and incondensable gas, and subjecting said relatively heavy, insufficiently converted portions to reconversion in a 40 separate heating element, and selectively introducing the heated products from said separate heating element into the reaction chamber or vaporizing chamber, as desired.

Referring to the accompanying drawing, illustrating one form of apparatus in which the invention may be carried out, raw oil charging stock may be supplied through a line 1, controlled by a valve 2 to a pump 3, and may pass through a line 4, controlled by valve 5, and a line 6 to a heating element 7. Any desired por-

tion of the raw oil may be diverted from line 4 and passed through a line 8, controlled by valve 9 to a fractionator 10 for preheating therein by contact with relatively hot vapors, assisting in their fractionation, and may pass from said fractionator, together with relatively heavy, insufficiently converted fractions, through a line 11, controlled by valve 12 to a pump 13 to further treatment, as will hereinafter be more fully described.

10 Heating element 7 may be disposed in any conventional form of furnace 14. The oil supplied thereto may be heated to any desired conversion temperature and is preferably maintained under a substantial superatmospheric 15 pressure. The heated products from said heating element 7 may pass therefrom through a line 15, controlled by a valve 16, into a line 17 and be passed to reaction chamber 18. Chamber 18 is preferably maintained under a sub- 20 substantial superatmospheric pressure, which may be substantially equal to or lower than that prevailing in heating element 7. The liquid and vaporized products from chamber 18 may be withdrawn from said chamber, preferably at 25 a point remote from their point of introduction thereto, through a line 19, controlled by a valve 20, and passed to a vaporizing chamber 21 30 wherein separation occurs.

Chamber 21 is preferably maintained under 35 a relatively reduced pressure, and, if desired, may be maintained under substantially atmospheric or sub-atmospheric pressure. The unvaporized residual products from chamber 21 may be withdrawn therefrom through a line 22 controlled by valve 23, for further treatment, or sent to storage, as desired, or a regulation may be effected and conditions controlled within chamber 21 so as to produce substantially dry coke as the residual product therein. In the 40 latter event, the residual, coke-like material may be permitted to remain within said chamber 21 until completion of the operation, and then removed therefrom. If desired, a plurality of chambers (not shown), similar to chamber 21 45 may be utilized, either alternatively or in parallel, permitting a prolonged operation of the process.

Vapors from chamber 21 may be withdrawn through a line 24, controlled by valve 25, and 50 may be subjected to fractionation in fractionator 10 to effect separation of the relatively heavy, insufficiently converted portions from the relatively light portions thereof. The relatively light components from said fractionator 10 may be 55

withdrawn through a line 26, controlled by valve 27 and passed to a condenser 28 where they may be subjected to condensation and cooling. Condensed distillate and incondensable gas from said 5 condenser may pass through a line 29, controlled by valve 30, and be collected in a receiver 31, from which distillate may be withdrawn through a line 32, controlled by valve 33. Incondensable gas may be released from said receiver through a line 34, controlled by valve 35. Any desired 10 amount of the distillate in receiver 31 may be withdrawn through a line 36, controlled by a valve 37 and passed via pump 38 through a line 39, controlled by a valve 40 to fractionator 10 to 15 assist in fractionation of the vapors therein.

The relatively heavy, insufficiently converted portions forming reflux condensate, either separately or in admixture with portions of raw oil which may be supplied to fractionator 10, may be 20 withdrawn from said fractionator through a line 41, controlled by valve 42 to a pump 43, as stated, to communicate with line 6 through which reflux condensate from fractionator 10 may pass, together with raw oil supplied directly to this 25 line from line 4, to heating element 7. However, any desired portion or all of the reflux condensate, either alone or in admixture with any desired portion of the raw oil charging stock passing from said fractionator 10 through line 41, pump 43 and line 6, may pass through a line 42, controlled by valve 43 to a heating element 44.

Heating element 44 may be disposed in any conventional form of furnace 45 wherein oil may be raised to any desired conversion temperature under any desired pressure. Heating element 44 may be preferably maintained at a higher temperature than that employed in heating element 7, while the pressure employed therein may be substantially the same or higher or lower, as desired, and may be substantially atmospheric or even sub-atmospheric. Heated products issuing from heating element 44 may be discharged through a line 46, controlled by valve 47, into a chamber 21, or may pass from line 46 through a line 48, controlled by valve 49, into a line 17 for passage into chamber 18. If desired, the heated products from heating element 44 may be passed to lines 48 and 47 and chambers 18 and 21, respectively, concurrently.

Pressures employed within the system may range from subatmospheric to superatmospheric pressures to as high as 2000 pounds or more per square inch. Substantially equalized or differential pressures may be employed throughout the 55 system, or in any of the zones thereof. Preferably, more severe conversion conditions are employed in heating element 44 than in heating element 7, and chamber 21 may be maintained under a substantially lower pressure than that prevailing in chamber 18, and the succeeding fractionating, condensing and collecting equipment may be maintained under substantially the same pressure as chamber 21. Conversion temperatures ranging from 750° to 1200° F., more or less may 60 be employed in heating elements 7 and 44.

In a specific example of an operation in which the principles of the invention may be obtained, a 24-26° A. P. I. gravity charging stock was charged to the heating element 7, and a transfer 70 temperature of approximately 915° F. was maintained, together with a pressure of about 300 pounds on said heating element and reaction chamber 18. Heating element 44 was maintained at a temperature approximately 1000° F., and a pressure of about 50 pounds per square inch was 75

maintained thereon, and in vaporizer 21, with an equalized pressure on the fractionator, condenser and receiver.

Under these conditions, a yield of approximately 50% of motor fuel, having anti-knock 5 value of approximately 65% benzol equivalent, (i. e., equal in anti-knock properties to a mixture of straight-run Pennsylvania gasoline and benzol containing 65% of benzol), and in addition, 25% of a heavy fuel oil residue was obtained. 10 Substantially no coke was formed, and the remaining product was gas.

When the same conditions were employed, using a 40-44° A. P. I. gravity Pennsylvania fuel oil as a charging stock, 65% of gasoline having a 15 benzol value of approximately 60% was obtained, and, in addition, approximately 15% of a good fuel oil was produced. Substantially no coke was formed, and the remaining product was gas.

It is to be understood that the above examples 20 are merely illustrative of one mode of carrying the invention into effect, and that various modifications may be made without departing from the underlying principles thereof.

I claim as my invention:

1. A process for the cracking of hydrocarbon oils, which comprises subjecting said oil to cracking conditions of temperature in a heating zone, passing the heated products to an enlarged reaction zone where further cracking takes place, 30 maintaining superatmospheric pressure in the heating zone and in the reaction zone, introducing all of the products of reaction to a reduced pressure zone wherein vapors separate from non-vaporous residue, removing the non-vaporous 35 residue and isolating same from the system, passing the evolved vapors from said reduced pressure zone to a fractionating zone where further separation occurs and wherein the heavier fractions condense as reflux condensate, passing regulated 40 portions of the reflux condensate from said fractionating zone to a separate heating zone, subjecting said reflux condensate in said separate heating zone to further cracking at an elevated 45 temperature higher than the temperature maintained in said first mentioned heating zone, and selectively directing said reflux condensate from said separate heating zone to the reaction zone and to the reduced pressure zone.

2. A process for the cracking of hydrocarbon 50 oil, which comprises subjecting said oil to cracking conditions in a heating zone, passing the heated products to an enlarged reaction zone where further cracking takes place, maintaining superatmospheric pressure in the heating zone 55 and in the reaction zone, removing all of the products of reaction through a common outlet and introducing same to a zone of reduced pressure where vapors separate from non-vaporous residue, passing the evolved vapors from said reduced 60 pressure zone to a fractionating zone where further separation occurs and where reflux condensate forms, passing regulated portions of the reflux condensate from said fractionating zone to a separate heating zone and there subjecting 65 said reflux condensate to further cracking at an elevated temperature higher than the temperature maintained in said first mentioned heating zone, and selectively directing said reflux condensate from said separate heating zone to the reaction zone and to the reduced pressure zone.

3. A process for the cracking of hydrocarbon oil, which comprises subjecting said oil to cracking conditions in a heating zone, passing the heated products to an enlarged reaction zone where fur- 75

- ther cracking takes place, maintaining superatmospheric pressure in the heating zone and in the reaction zone, removing all of the products of reaction at a point remote from the point of introduction of the heated products to said reaction zone and introducing same to a zone of reduced pressure where vapors separate from non-vaporous residue, passing the evolved vapors from said reduced pressure zone to a fractionating zone.
- 5 where further separation occurs and where reflux condensate forms, passing regulated portions of

the reflux condensate from said fractionating zone to a separate heating zone and there subjecting said reflux condensate to further cracking at an elevated temperature higher than the temperature maintained in said first mentioned heating zone, and selectively directing said reflux condensate from said separate heating zone to the reaction zone and to the reduced pressure zone.
